STETHOSCOPE

Julius Erandenburg, New York, N. Y., assignor to
 Brandenburg Instrument Co. Inc., a corpora-
 tion of New York

Application March 14, 1944, Serial No. 526,357

7 Claims. (Cl. 181—24)

1

This invention relates to stethoscopes. Broadly, it is an object of my invention to provide a stethoscope which gives improved amplification of the pulsation of heart murmurs.

More particularly, an object of my invention is to provide a stethoscope which equalizes the tone of heart murmurs, giving a more uniform pitch, at the same time providing a certain amount of reflection of sound within the housing of the stethoscope.

A further object of my invention is to provide a pair of parallel diaphragms placed at such an angle within the housing of the stethoscope so that vibration of sound or other disturbances is eliminated, such as when the stethoscope is moved by the physician over the skin or hairs of the body. Since the murmurs of the thoracic viscera are only faintly audible it is of the utmost importance to obtain better vibration of the resonance plates. I have therefore provided a pair of angular and parallel resonance plates, one with holes and the other with slots for facilitating movement of the sound waves and to provide better vibration in order to give a more definite sound tone with greater resonance.

Another object is to provide a stethoscope which is easily assembled so that the parts may be readily replaced in the event it should become necessary so to do.

For a fuller understanding of the nature and objects of my invention, reference is had to the following detailed description in connection with the accompanying drawing, in which Fig. 1 is a vertical longitudinal view, with parts partly broken away. Fig. 2, partly in section, is a front elevation of the stethoscope head, showing the parts partly broken away.

Referring to the drawing, numeral 10 represents the side housing wall of the stethoscope having an internal thread 11 and an internal straight wall 12. Below the thread 11 there is an internal shoulder 13 which acts as a seat for a flange 14 of upper diaphragm 15. Housing 10 also has an external shoulder 16 which may act as a stop for the knurled clamping ring 17. Below shoulder 16 the lower housing portion has an external thread 18 to receive the threaded clamping ring 17.

Clamping ring 17 has an internal thread 19 which coats with the external thread 18 and has an angular shoulder 20 for clamping an outer diaphragm 21 within a space created by the angular shoulder 20 and the parallel angular edge 22 of the lower portion of the housing 10. Diaphragm 21 is preferably made of Celluloid. How-

ever, this diaphragm may also be made of exceptionally thin metal or other types of plastic.

At the upper portion of the stethoscope a cap portion 23 has a depending annular flange 24 with an upper smooth face 25 and a lower external threaded portion 26 coating with the internal threaded portion 11 of the housing 10. The depending flange 24 of cap 23 has a horizontal end 27 which clamps the flange 14 of the upper diaphragm 15 against the internal shoulder 13 of the housing wall 10. The inner wall of cap 23 and lower portion of housing 10 are in vertical alignment. The upper portion of cap 23 has a raised portion 28 in order to provide sufficient material for an internally threaded opening 29 to receive the lower external threaded portion 30 of Y member 31.

Y member 31 is hollow throughout with raised portions 45—46 at the upper extremities to receive and hold the rubber tubes which are placed over the angular arms of the Y member 31. The lower end of Y member 31 is formed so that it is flush with the inside of cap 23.

Behind outer diaphragm 21 and clamped by 25 a flange 32 between the angular shoulder 20 of the clamping ring 17 and the angular edge 22 of the lower portion of the housing, an intermediate diaphragm 33 is firmly positioned. Diaphragm 33 has an outer flange 32 and a vertical portion 34 which rests against the inner wall of the lower portion of housing 10. It is then bent in a frusto-conical shape having an angular portion 35 and a central opening 36. A series of small holes 37 are spaced at regular intervals 35 around the angular portion 35 of the intermediate diaphragm 33.

As heretofore described, upper diaphragm 15 is firmly fixed in position by its flange 14 clamped between the lower end 27 of the depending flange 24 and the internal shoulder 13. The diaphragm is then bent upward with a vertical portion 38 resting against the inner wall of the annular flange 24. It is then bent in a frusto-conical shape with an angular wall 39 which is in parallel relationship to angular wall 35 of the intermediate diaphragm 33. The upper portion of upper diaphragm 15 has a small horizontal flange 40 and a central opening 41. The annular wall 39 has a series of slots 42 which lead into the central opening 41.

The upper diaphragm 15 and the intermediate diaphragm 33 are made preferably of exceptionally thin metal so that they are sensitive to the movement of sound waves. It should be noted 55 that the small horizontal flange 40 of the upper

diaphragm 15 is not in contact with the inner wall of the cap 23 in order to permit free vibration of the upper diaphragm.

When stethoscope is moved over the skin of a person the outer diaphragm 21 receives the vibrations and transmits the same to the interior of the chamber, the sound entering the vortex in the intermediate diaphragm 33 and passes through openings 32 and the central opening 36 and then is received by the upper diaphragm 15 which further directs the vibrations toward the central opening 41 of the upper diaphragm, and thence through the hollow channels of Y member 31, and thence through the rubber tubes (not shown) leading to the ear pieces. The intermediate and upper diaphragms 33 and 15, respectively, retard reflection of the sound between the inner walls of the housing and cap and direct the sound toward the bottom of the Y member, the walls of both the intermediate and upper diaphragm vibrate in unison and create a lower and more uniform pitch which is more readily discerned by the person using the stethoscope.

It is obvious that various changes and modifications may be made in the various details of constructions without departing from the general spirit of the invention as set forth in the appended claims.

I claim:

1. A stethoscope comprising a transmitter head, said head having a sound receiving chamber, a pair of diaphragms conically shaped with central openings and spaced in parallel relationship to one another within said chamber, an outer diaphragm for transmitting sound waves into said chamber and a passageway for leading the sound from said chamber.

2. A stethoscope comprising a transmitting head, said head having a sound receiving chamber, an upper diaphragm having a central opening, and slotted angular walls, an intermediate diaphragm having openings in an angular wall and a central opening, said intermediate and upper diaphragms being fixed within said chamber and the angular walls of said diaphragms being in parallel relation, an outer diaphragm for transmitting sound to said inner chamber, and a passageway leading from said chamber.

3. A stethoscope comprising a transmitting head, said head having a housing and a cap an outer diaphragm, an intermediate diaphragm, an

upper diaphragm, said housing having an annular ring for clamping an outer diaphragm and an intermediate diaphragm within said housing, an upper diaphragm fixed between said intermediate diaphragm and said cap, said intermediate diaphragm and upper diaphragm having central openings and angular walls in parallel relation to one another and a passageway leading from said chamber.

4. A stethoscope comprising a transmitting head having a sound receiving chamber, said head having a housing, a cap with a depending annular flange fitted within said housing, an outer clamping ring fitted within said housing opposite said cap, said clamping ring holding an outer diaphragm and an intermediate diaphragm within said chamber, said cap holding an upper diaphragm within said chamber, said intermediate and upper diaphragms having center openings and angular walls spaced in parallel relation to one another, and a central passageway leading from said chamber.

5. A stethoscope comprising a transmitting head, said head having a hollow chamber, a pair of frusto-conical shaped resonance plates within said chamber in parallel relationship to one another, said resonance plates having central openings, an outer diaphragm for transmitting sound waves into said chamber, and a Y-member with hollow passageways for leading the sound from said chamber.

6. A stethoscope comprising a transmitting head with a chamber, said head having an opening at one end, a hollow terminal leading into said opening, a pair of angular resonance plates spaced apart in parallel relation, said plates having central openings, and an outer diaphragm at the opposite end for leading sound waves into said chamber.

7. A stethoscope having a transmitting head and a chamber, an upper resonance plate within said chamber and an intermediate resonance plate in parallel relation to said upper resonance plate, said upper and intermediate resonance plates having angular walls with openings thereon, each of said plates having a central opening, a flexible diaphragm for leading sound waves into said chamber, and an opening at the opposite end of said housing for leading sound waves out of said chamber.

JULIUS BRANDENBURG.
